[57] **CLAIM**

An ornamental design for a paint can holder, as shown and described.

DESCRIPTION

FIG. 1 is a perspective view showing the top, front and left side of the paint can holder, showing my preferred design; FIG. 2 is a front elevational view of the design of the paint can holder shown in FIG. 1;

FIG. 3 is a rear elevational view of the design of the paint can holder shown in FIG. 1;

FIG. 4 is a right side elevational view of the design of the paint can holder shown in FIG. 1; and

FIG. 5 is a left side elevational view of the design of the paint can holder shown in FIG. 1;

FIG. 6 is a top plan view of the design of the paint can holder shown in FIG. 1; and,

FIG. 7 is a bottom plan view of the design of the paint can holder shown in FIG. 1.

The broken line showing of a belt and a paint can is for illustrative purposes only and forms no part of the claimed design.
